(57) **CLAIM**

We claim the ornamental design for an electronic cigarette vaporizer mouthpiece, as shown and described.

DESCRIPTION

FIG. 1 is a top front perspective view of an electronic cigarette vaporizer mouthpiece.

FIG. 2 is an enlarged partial view of the electronic cigarette vaporizer mouthpiece depicted in FIG. 1.

FIG. 3 is a front elevational view of the electronic cigarette vaporizer mouthpiece depicted in FIG. 1.

FIG. 4 is a rear elevational view of the electronic cigarette vaporizer mouthpiece depicted in FIG. 1.

FIG. 5 is a left side elevational view of the electronic cigarette vaporizer mouthpiece depicted in FIG. 1.

FIG. 6 is a right side elevational view of the electronic cigarette vaporizer mouthpiece depicted in FIG. 1.

FIG. 7 is a top plan view of the electronic cigarette vaporizer mouthpiece depicted in FIG. 1; and,

FIG. 8 is a bottom plan view of the electronic cigarette vaporizer mouthpiece depicted in FIG. 1.

The broken lines in the drawing depict portions of the electronic cigarette vaporizer mouthpiece that form no part of the claimed design.
